US00D498844S

(12) **United States Design Patent** (10) Patent No.: **US D498,844 S**
Diamond et al. (45) Date of Patent: **** Nov. 23, 2004**

(54) **DUAL LUMEN CATHETER WINGED BIFURCATION**

(75) Inventors: **Jordan Diamond**, Salt Lake City, UT (US); **Jason Stats**, Woods Cross, UT (US)

(73) Assignee: **C. R. Bard, Inc.**, Murray Hill, NJ (US)

(**) Term: **14 Years**

(21) Appl. No.: **29/189,202**

(22) Filed: **Aug. 29, 2003**

(51) LOC (7) Cl. **24-02**

(52) U.S. Cl. **D24/130**

(58) Field of Search **D24/130, 129, D24/112, 114, 146-7, 127-8, 164.08, 165.03, 165.04, 177, 198, 174, 263; 600/573, 567, 583, 576; 604/164, 164.03, 164.04, 164.07**

(57) **CLAIM**

The ornamental design for a dual lumen catheter winged bifurcation, as shown and described.

DESCRIPTION

FIG. 1 is a perspective view of a dual lumen catheter winged bifurcation;

FIG. 2 is a left elevation side view of the dual lumen catheter winged bifurcation of FIG. 1.

FIG. 3 is a right elevation side view of the dual lumen catheter winged bifurcation of FIG. 1.

FIG. 4 is a top elevation view of the dual lumen catheter winged bifurcation of FIG. 1.

FIG. 5 is a bottom elevation view of the dual lumen catheter winged bifurcation of FIG. 1.

FIG. 6 is a front elevation view of the dual lumen catheter winged bifurcation of FIG. 1; and,

FIG. 7 is a rear elevation view of the dual lumen catheter winged bifurcation of FIG. 1.
